UNITED STATES PATENT OFFICE

1,934,593

SIGNALING DEVICE

Ernst Durst and Georg Ehret, Stuttgart, Germany, assignors to Robert Bosch Aktiengesellschaft, Stuttgart, Germany

Application November 24, 1928, Serial No. 321,722.
and in Germany November 28, 1927

4 Claims. (Cl. 177—7)

The present invention relates to acoustical signaling devices, particularly for motor vehicles, and more particularly of the type which have a diaphragm electro-magnetically set in oscillation. In signaling devices of this type the armature of the electro-magnet is usually connected with the diaphragm by means of a bolt. In order to guide the bolt axially, it is either screwed or riveted to a guide spring or slides in a bush. Both known types of construction possess certain disadvantages. The introduction of the bolt rigidly connected with the guide spring is cumbersome, whilst the sliding guide damps the vibrations. If the bolt has too much play in the bush the guidance of the vibrating system is open to objection and vibrations can be set up which are not in the desired direction. If the play is too small excessive friction is set up thereby again damping the vibrations. These disadvantages are overcome by the invention which also introduces a considerable simplification of construction, in that the free end of the armature bolt is, according to the invention mounted by means of a pointed or rounded end in a depression provided in a leaf spring, preferably secured under tension at both ends. One form of construction of the invention is shown in the accompanying drawing in which:— Figure 1 is a vertical central section of a signaling device. Figure 2 is a longitudinal section of the guide spring, and, Figure 3 is a plan view of the same. The housing consists of the two portions *a* and *b* the sinuous diaphragm *c* being held at its edge between the flanges of the same. Figure 1 only shows a portion of the mouth piece *d*. The electro-magnet *e* is mounted in the portion *a* of the housing in any suitable manner. The armature *f* of the electro-magnet is mounted on a bolt *g* secured in the center of the diaphragm *c*. The core *h* of the magnet is bored longitudinally therethrough to allow free passage of the armature bolt *g* the top end of which is guided. For this purpose a leaf spring *i* is provided having holes *k* at both ends for its attachment to the housing by means of screws *m*.

An impressed recess or bulge *n* into which the pin *o* of the armature bolt projects is located centrally of the leaf spring. The free end of the bolt is thereby guided. The leaf spring *i* is preferably tensioned by bending its ends downwards (see Figure 2) so that on tightening up the screws *m* the central portion of the spring is bent down-

twards. By placing spring *i* under an initial tension, the spring will follow the free end of the bolt in its vibratory movement and prevent the unseating of the bolt. If firm contact is not always maintained between spring *i* and the end of bolt *g* the quality of the sound emitted will be impaired. By having the free end of bolt *g* rounded or pointed, the tension of spring *i* causes the bolt to remain firmly centered within the recess *n* and thereby prevent lateral vibrations of the bolt. Instead of forming the recess *n* directly in the spring *i*, it is obvious that it may be formed in a block carried by the leaf spring.

In order to be able to mount the leaf spring between the upper wall of the housing and the electro-magnet, the portion *a* of the housing is provided at the top with a dished portion *p*.

What we claim and desire to secure by Letters Patent is:—

1. An acoustic signaling device comprising a housing, a diaphragm mounted within said housing, an electromagnet, an armature for said electromagnet including a bolt member rigidly secured at one end to said diaphragm, and a leaf spring member secured to said housing and flexed in the direction of said diaphragm by a flexure greater than the maximum outward displacement of the diaphragm, said spring member and bolt member being provided with interacting means for supporting and maintaining self-centered the free end of said bolt member and preventing lateral movement between the bolt member and electromagnet while permitting longitudinal movement therebetween.

2. An acoustic signaling device comprising a housing, a diaphragm mounted within said housing, an electromagnet, an armature for said electromagnet including a bolt member rigidly secured at one end to said diaphragm and having a rounded free end, a leaf spring member having a rounded recess for embracing the rounded free end of said bolt member and supporting the same against lateral vibration, and means for securing said spring to said housing, said spring being flexed in the direction of said diaphragm by a flexure greater than the maximum outward displacement of the diaphragm.

3. An acoustic signaling device comprising a housing, a diaphragm mounted within said housing, an electromagnet, an armature for said electromagnet including a bolt member rigidly secured at one end to said diaphragm, a leaf spring secured to said housing and flexed in the direction of said diaphragm by a flexure greater than the maximum outward displacement of the diaphragm.

phragm, and a ball and socket connection between the free end of said bolt member and said leaf spring.

4. An acoustic signaling device comprising a housing, a diaphragm mounted within said housing, an electromagnet, an armature for said electromagnet including a bolt member rigidly secured at one end to said diaphragm and having a rounded free end, a leaf spring provided with a

rounded cup-shaped recess for engaging the rounded free end of said bolt and supporting the same against lateral vibration, and means for securing both ends of said spring to said housing, said spring being flexed in the direction of said diaphragm by a flexure greater than the maximum outward displacement of said diaphragm.
